UNITED STATES PATENT OFFICE

FRANK B. TOTMAN, OF ALTADENA, CALIFORNIA, ASSIGNOR TO GEORGE J. KUHRTS, JR.,
OF LOS ANGELES, CALIFORNIA

MIXER

Application filed June 11, 1929. Serial No. 370,090.

My present invention relates to mixers, sometimes known as pug mills, particularly for mixing plastic materials, such as asphalt, and the like.

5 The objects of this invention are: first, to provide a mixer whereby the charges or batches of materials mixed therein may be easily, quickly and completely discharged by turning the receptacle, containing the materials and in which the materials are mixed, up side down; second, to provide mechanism for dumping and operating mixers in such manner irrespective of the size of the mixer; third, to provide a mixer of this class in which 10 the power unit for operating the paddles or agitators of the mixer is used for dumping or turning the mixer receptacle up side down, and in which the dumping or discharging operation is performed at relatively slow 15 speed so that the latter operation may be easily controlled; fourth, to provide a mixer of this class in which the mixer receptacle is normally held in an upright position by a brake mechanism, and in which the brake 20 mechanism is released simultaneously by unitary means with the application of the power to the mechanism for rotating the receptacle for dumping or discharging the same, and also one in which the brakes are applied when 25 the power for rotating the receptacle is disconnected; fifth, to provide a mixer of this 30 class in which the paddles or agitators are operated at substantially normal speed during the dumping or discharging operation; sixth, 35 to provide a dumping or discharging mechanism for mixers of this class, which mechanism may be easily controlled so that the mixing receptacle, when rotated, may be stopped at any position desired; and, 40 seventh, to provide a novelly constructed machine of this class, and one which is relatively simple and economical of construction, efficient, durable and which will not readily deteriorate or get out of order.

45 With these and other objects in view as will appear hereinafter, my invention consists of certain novel features of construction, combination and arrangement of parts and portions as will be hereinafter described in detail and particularly set forth in the ap-

pended claims, reference being had to the accompanying drawings and to the characters of reference thereon which form a part of this application in which:

Figure 1 is a plan view of my mixer in its 55 preferred form of construction; Fig. 2 is a side elevational view thereof; Fig. 3 is a fragmentary sectional view thereof taken through 3—3 of Fig. 1; Fig. 4 is a sectional end elevational view thereof taken at 4—4 of Fig. 1; 60 Fig. 5 is a fragmentary sectional view thereof taken through 5—5 of Fig. 1; and, Fig. 6 is a sectional view thereof taken at 6—6 of Fig. 5.

Like characters of reference refer to similar parts and portions throughout the views 65 of the drawings.

The present embodiment of my invention, as illustrated in the drawings, is in a stationary mixing plant, but it will be understood that my mixer is not limited to such use. As 70 shown in the drawings, the mixing receptacle of my machine is supported at its opposite end on pedestals or journals 1 and 2 which are mounted on the upper ends of suitable 75 foundations 3 and 4 which are positioned at the opposite sides of and contiguous to a runway on or through which trucks or other conveyances may pass. These trucks or other 80 conveyances may pass immediately under the mixing receptacle and remain underneath the receptacle until the same are charged with the desired loads.

The mixing receptacle, designated 11, is 85 here shown as divided into three compartments, namely, the mixing compartment 11a and two gear compartments 11b and 11c at the opposite ends thereof. To the outer sides of the end heads 11d and 11e which form the outer walls of the gear compartments 11b 90 and 11c respectively of the receptacle, are provided large trunnions 12 and 13, the axes of which extend approximately through the center of gravity of the receptacle. These trunnions are rotatably mounted in the journals 1 and 2.

Extending longitudinally through the mixing compartment of the receptacle 11 are a pair of mixing paddle supporting shafts 21 and 22. These shafts are positioned par- 100

allel to each other at the opposite sides of the longitudinal axis of the receptacle. On these shafts are mounted in spaced relation a plurality of agitating, mixing, or paddle members 23. On the end of the shaft 21 which extends into the compartment 11b is mounted a gear 24 which meshes with a gear 25 mounted on the inner end of the drive shaft 14. On the other end of the shaft 21 which extends into the compartment 11c is mounted a larger gear 26 which meshes with a similar gear 27 mounted on the coincident end of the shaft 22, thus driving the shafts 21 and 22 and the paddles thereon in opposite directions.

The drive shaft 14 is coaxial with the trunnion 12 and is rotatable therein. This shaft extends a considerable distance beyond the end of the trunnion 12 and is journaled at its outer end on a journal 15. At the latter end of the drive shaft 14 is mounted a drive gear 16 which is driven by a drive pinion 17 mounted on the shaft of the electric motor 18.

On the drive shaft 14 is mounted a small pulley 31 which is connected by a belt 32 to a large pulley 33. This pulley 33 is rotatably mounted on a counter shaft 34 which is positioned parallel to the drive shaft at one side thereof. To one side of the pulley is secured a clutch member 35 which is here shown as an internal cone clutch member. On the shaft 34 is keyed but slidably mounted a cone clutch member 36 which is adapted to be shifted into engagement with the clutch member 35 for rotating the counter shaft. On the counter shaft, at the side of the pulley 33 opposite the clutch, is mounted and keyed a small sprocket 37 which is connected by a link belt or chain 38 to a large sprocket wheel 39 which is mounted on the end of the trunnion 12 which extends through the journal 1. This sprocket 39, when rotated, is adapted to rotate the mixing receptacle for dumping or discharging the contents therefrom.

The cone clutch member 36 is adapted to be shifted into and out of engagement with and from the clutch member 35 by a clutch lever 41 which is pivotally mounted at its lower end on a bracket 42 which may be supported on the foundation 3. The clutch member 36 is normally held in disengaged relation from the clutch member 35 by a spring 43 which is attached to the upper end of the clutch lever. The clutch is controlled by a control lever 44 which is secured at its lower end to a rockshaft 45 which is rotatably mounted on a framework 46. This framework supports an operator's platform 47 through and above which the upper end of the control lever 44 extends. The control lever is held in a receded or backward position by a dog 48 which engages a notched quadrant 49 mounted on the platform 47.

To the control lever 44 is attached a cable 50, the attachment being between the pivotal axis of the control lever and the platform 47. This cable extends around a sheave 51 and thence to the upper end of the clutch lever 41. Thus, when the control lever 44 is forced forwardly, the clutch lever 41 is shifted forcing the cone clutch member 36 into engagement with the clutch member 35, causing the mixing receptacle to be rotated. 75

On the end of the trunnion 12 which extends beyond the journal 1, is also mounted a brake drum 61 around which extends a brake band 62. One end of the brake drum is fixed to a bracket 63 which may be mounted on the foundation 3. On the upper end of the bracket 63 is pivotally mounted a rocker arm 64. To the end of the rocker arm extending toward the brake drum is pivotally connected the other end of the brake band, as shown best in Fig. 4. The rear end of the rocker arm 64 is pivotally connected by a link 65 to the end of a brake arm 66 which is secured to the rockshaft 45. Thus when the control lever 44 is forced forwardly, causing the clutch to be engaged, the brake band is released, and when the control lever 44 is forced backwardly, the brake is applied and the clutch is disengaged. 90

The operation of my mixer is briefly as follows:

The mixer is started with the control lever 44 in its backward position, as shown in Fig. 4. The mixing compartment is then charged with the materials to be mixed. The mixing operation is continued until the materials are mixed to the desired degree. A truck or other conveyance is placed directly below the mixing receptacle. The control lever 44 is then shifted forwardly which operation releases the brake and shifts the clutch members into engagement for permitting the mixing receptacle to be rotated about its axis, while the agitators continue to rotate at substantially the normal speed with respect to 100 the receptacle. If desired, the receptacle may be held in a position with its open side downwardly, or the rotation of the receptacle may be continuous until it is again right side up. The lever 44 is then drawn backwardly 115 which holds the mixing receptacle in its normal upright position for receiving the charge.

Though I have shown and described a particular construction, combination and arrangement of parts and portions, I do not 120 wish to be limited to this particular construction, combination and arrangement, but desire to include in the scope of my invention the construction, combination and arrangement substantially as set forth in the appended claims. 125

Having thus described my invention, what I claim as new and desire to secure by Letters Patent is:

1. In a machine of the class described, a ro-

tatable receptacle, agitators mounted therein, means for rotating the agitators, speed reduction means connecting said last mentioned means to said receptacle for rotating the same by said first means, and brake means in connection with the receptacle for checking the rotation thereof.

5. In a machine of the class described, a rotatable receptacle, agitators mounted therein, means for rotating the agitators, speed reduction means connecting said last mentioned means to said receptacle for rotating the same by said first means, brake means in connection with the receptacle for checking the rotation thereof, and unitary means for controlling said speed reduction means and said brake means.

10. In a machine of the class described, a rotatable receptacle, agitators mounted therein, means for rotating the agitators, speed reduction transmission means adapted to connect said first mentioned means to said receptacle, a clutch for connecting said transmission means to said first mentioned means and said receptacle, and means for checking the rotation of the receptacle.

15. In a machine of the class described, a rotatable receptacle, agitators mounted therein, means for rotating the agitators, speed reduction transmission means adapted to connect said first mentioned means to said receptacle, a clutch for connecting said transmission means to said first mentioned means and said receptacle, means for checking the rotation of the receptacle, and unitary means for actuating said clutch and said checking means.

20. In a machine of the class described, a rotatable receptacle, agitators mounted therein and movable therewith and relative thereto when said receptacle is stationary and when rotated, a unitary shaft coaxial with the axis of rotation of the receptacle, a countershaft, a clutch on the countershaft, speed reduction transmission means connecting the first shaft to the clutch, other transmission means connecting said countershaft to the receptacle, and means for controlling said clutch.

25. In a machine of the class described, a rotatable receptacle, agitators mounted therein and movable therewith and relative thereto when said receptacle is stationary and when rotated, a unitary shaft coaxial with the axis of rotation of the receptacle, a countershaft, a clutch on the countershaft, speed reduction transmission means connecting the first shaft to the clutch, other transmission means connecting said countershaft to the receptacle, means for checking the rotation of the receptacle, and unitary means for controlling the clutch and the checking means.

30. In a machine of the class described, a pair of journals, a receptacle provided with trunnions at its opposite sides and rotatably

35. mounted with said trunnions in said journals, agitators in said receptacle, a shaft extending through one of said trunnions for driving the agitators, means in connection with the trunnions for checking the rotation of the receptacle, reduction power transmission means connecting said shaft to said trunnion, and unitary means for controlling said transmission means and said checking means.

40. In a machine of the class described, a rotatable receptacle, a drive shaft coaxial with the axis of rotation of the receptacle and extending thereto, agitators in said receptacle connected to said shaft, speed reduction means, a clutch in association with said speed reduction means and adapted to connect said drive shaft and said receptacle through said speed reduction means, and means for actuating the clutch.

45. In a machine of the class described, a rotatable receptacle, agitators mounted therein, means for operating the agitators, a clutch adapted to connect said first mentioned means to said receptacle for rotating the same, means for checking the rotation of the receptacle, and unitary means for controlling the clutch and the checking means.

50. In a machine of the class described, a support, a receptacle mounted on the support and adapted to turn thereon on an axis, agitators mounted in the receptacle, means for rotating the agitators, means for connecting the last mentioned means to said receptacle for turning the same about its axis, brake means in connection with the receptacle for checking the movement thereof, and unitary means for controlling and simultaneously actuating said operative connecting means and said brake means.

55. In a machine of the class described, a rotatable receptacle, agitators mounted therein, means coaxial with the axis of rotation of the receptacle for rotating the agitators, means adapted for periodic connection with the receptacle for periodically and completely rotating the same in the same direction as the last mentioned means but at a slower speed, and means for checking the rotation of the receptacle when the receptacle rotating means is disconnected.

60. In testimony whereof, I have hereunto set my hand at Los Angeles, California this 22nd day of May 1929.

FRANK B. TOTMAN.
